COMBINATION AMPLIFIER AND SPEAKER CABINET

Paul B. Spranger, Fullerton, Calif., assignor to Columbia
Broadcasting System, Inc., New York, N.Y., a corpo-
ration of New York

Filed Mar. 25, 1966, Ser. No. 1,637

Term of patent 14 years

(Cl. D26—14)

FIGURE 1 is a perspective view of a combination amplifier and speaker cabinet, embodying my new design; FIGURE 2 is a front elevation thereof;

FIGURE 3 is a transverse section thereof taken on line 3—3 of FIGURE 2, for the purpose of indicating surface contour only;

FIGURE 4 is a rear elevation thereof;

FIGURE 5 is a top plan view thereof;

FIGURE 6 is a side elevation thereof as viewed from the right in FIGURE 2;

FIGURE 7 is a side elevation thereof as viewed from the left in FIGURE 2; and

FIGURE 8 is a bottom plan view thereof. The dominant features of the design reside in the portions shown in solid lines.

I claim:

The ornamental design for a combination amplifier and speaker cabinet, substantially as shown and described.
